DOUBLE FRAME BED

Joseph H. Pilates, New York, N. Y.

Application April 19, 1948, Serial No. 21,978

2 Claims. (Cl. 5—210)

1

The present invention relates to a special bed or couch which is made preferably of metal and particularly to a bed having rocking sections sustained by two or three springs imparting the total resiliency to the whole.

The main object of my invention is to provide a bed or couch of the character indicated which has two rocking frame portions mounted upon the bed frame side by side and prevented from collapsing toward the center by the springs which are mounted as tension springs between the lower portions of the two frame portions.

Another object is to have such a bed or couch which uses a minimum of springs and tends to cause a person lying on the same to gravitate toward the center of the bed.

A further object is to have such a bed which has adjustable supports which may be brought up into supporting contact with the two frame members to support them positively along the center of the bed.

It is also an object to have the head end of the bed adjustable either to upright position or to be released from the bed altogether.

Other objects and advantages of the invention will appear more fully in detail as the specification proceeds.

In order to bring out the features of this invention comprehensively, the latter is illustrated on the accompanying drawings forming part hereof, and in which,

Figure 1 is a plan view of a bed or couch made according to my invention and embodying the same in a practical form;

Figure 2 is a side elevation of the same bed, as seen from the bottom in Figure 1;

Figure 3 is a transverse section of the bed taken on line 3—3 in the same Figure 1;

Figure 4 is a horizontal section taken on line 4—4 in Figure 3;

Figure 5 is a fragmentary detail view; and

Figure 6 is a side elevation of the parts shown in Figure 5.

Throughout the views, the same reference numerals indicate the same or like parts.

Many types of beds have been used from time to time, and springs for the same have often contained a large number of individual springs, but it is desirable to use a minimum of springs to avoid breakdown or partial collapse of portions of the bed springs by using more firm structures which use only two or three springs to allow center sagging to a limited extent. It is also desirable to be in a position to prevent sagging altogether upon occasion, and to shift

2

the head of the bed when desired, and I have found it quite easy to design a bed with these characteristics, as I shall immediately proceed to describe.

Hence, in the practice of my invention, and referring now again to the accompanying drawings, a bed, generally indicated at 7, primarily includes an outer frame preferably made of tubing or pipe and of substantially rectangular form as shown at 8 with side members and head end 9, 10 and 11, respectively. This frame is indirectly supported upon the legs 12, 13, 14, etc., attached to the lower side frame members 15, 16 beneath side members 10 and 9 and having upright posts thereon at 17, 18, 19, etc., directly supporting the upper frame members 9 and 10 and thereby the frame 8.

Within the outline of frame 8 are a pair of narrow frame members generally indicated at 20, 21 which have their side edges 22 and 23 hinged to the main frame members 9 and 10 by means of enveloping straps 24, 24, 24, etc., of figure 8 form. These interior frames have their inner side portions 25 and 26 closely juxtaposed but out of actual contact, said portions being secured to the side members 22 and 23 by means of frame ends 27, 29, 28, 30, respectively, while a plurality of longitudinally arranged straps 31, 31, 32, 32 are connected at the ends thereof to the ends 27 to 30 of said interior frames. Across these straps just mentioned, a group of transverse straps 33, 34, 35, 36 are spaced apart and secured both at their ends to the frame side portions 22, 23, 25 and 26 and also to the longitudinal straps just described, so that these inner frames are provided, as it were with lattice work areas for supporting a mattress or the like. Beneath the straps 35 and 36 or both frames are secured downwardly projecting reinforcing angle members 37, 38, etc., which have their bottom apices 39, 40 interconnected by tension springs 41 (one shown). When a person lies upon the middle of the bed, the inner portions of inner frames 20, 21 at 25, 26 tend to become depressed as far as allowed by springs 41.

However, sometimes such a central position is not desired but rather a flat and substantially unyielding bed. Hence, as best seen in Figures 3 and 4, upon the lower frame members 15 and 16 at the portions where the legs connect therewith, are fixtures 42, 43, etc., to which are pivoted trunnions 44, 45 at the spaced ends of the short arms 46, 47 between which are fixed a transverse tubular member or pipe 48 upon which the arched ends 49, 50 of supporting member 51 are

fixed. The trunnions 44 and 45 are held in position by suitable wing screws, so that releasing these screws will allow the supporting units 48, 49, 50, 51 to be swung about the trunnions to the position shown in Figures 3 and 4, wherein the cross member 51 directly supports the inner side members 25 and 26 of the inner frames. When the supports are swung down with cross member 51 spaced below the inner frames, the latter then depend on springs 41 to support the weight imposed on the center of the bed in resilient manner. Thus a choice is available for supporting the person using the bed on a firm flat supporting area, or upon a centrally yielding section causing him to gravitate toward the center, at least to a limited degree.

The bed may be provided with a special head or high end which is suitable for attaching exercising devices thereto. The upright end frame 52 shown best in Figures 5 and 6, although also partly shown in Figures 1 and 2, includes the two upright posts connected at 53, 54 by top frame member 55 and a reinforcing cross member 56 spaced below the latter. At the bottom, the side members 53 and 54 are bent horizontally under the upper frame 8 to form bottom members 56, 57 connected together by a bottom cross piece 58 connected to holes 59 in said members 56 and 57 by a through bolt or the like, while further in between lower frame members 15 and 16 a cross member 60 is mounted for the present purpose. Of course, a pair of short studs extending merely a limited distance toward each other would also serve this purpose. Upon each of the two bottom members 56 and 57 are pivotally mounted by pivots 62 (one shown) a hook 61 adapted to hook over transverse member 60 and provided with a handle 63, while a spring 64 attached at 65 upon each bottom member tends to pull back or raise the hook. The bottom members have a spacing member 66 projecting rigidly upward against the upper frame portion 22, for example, to prevent raising of the bottom portions of this upright frame 52. The manually releasable hooks normally engage upon the mentioned cross member 60 or the studs if used, while the side uprights 53 and 54 are attached to the outer frame end 11 by means of screws or pins 67 and 68. If the manual hooks are released and these last mentioned pins or screws are removed, the whole end frame with its bottom members 56 and 57 as well as upright posts 53 and 54 with their transverse portions 55 and 56 may be bodily removed from the bed. Replacing this frame means, of course insertion of pins or screws 67

and 68 and locking manual hooks 61 on member 60, when the frame may be used for supporting various devices.

The bed may thus be used with, or without facilities for exercising, and as a flat couch or bed or as a partly centrally yielding bed structure, as desired.

Manifestly, variations may be resorted to and parts and features may be modified or used without others within the scope of the appended claims.

Having now fully described my invention, I claim:

1. A bed comprising a rigid rectangular frame 15 affording a pair of side rails and two rectangular framed members disposed between said side rails and together forming a surface for the support of a person's body, said members being hinged to said side rails and so designed and 20 constructed that when the bed is occupied by a person's body the central longitudinal portion thereof may be disposed substantially below the level of said side rails and the outer longitudinal edges thereof remain at substantially the 25 level of said side rails so that the surface forms a dihedral angle having sides sloping downwardly toward the longitudinal center line from said side rails, and resilient means under tension normally opposing the angular downward 30 movement of the said two members.

2. A bed according to claim 1, wherein means are provided whereby the two said framed members may be releasably locked to prevent the angular downward movement of the said members.

JOSEPH H. PILATES.
